HEAT RESPONSIVE SHUT-OFF VALVE

Luther D. Lovekin, Villa Nova, Pa., assignor to
Kitson Company, Philadelphia, Pa., a corpora-
tion of West Virginia

Application September 25, 1931
Serial No. 565,108

5 Claims. (Cl. 137—162)

The subject of my invention is a valve which may be used for shutting off the gas supply to an apartment, residence, shop, store, factory or other place of consumption. My novel valve may be conveniently, but is not necessarily, used in conjunction with a gas meter. My valve consists primarily of a movable valve member retained in open position by a fusible disk or other member and stressed to closed position by gravity or by gravity and a spring. It is an important feature of my device that the fusible member be held at two portions on opposite sides of that portion of the fusible member which is intended to be broken when the fusible member melts or is shorn and that the fusible member be held on at least two faces at each portion. This may be accomplished in my device by clamping the fusible element at its inner periphery on the casing and by clamping the fusible member on its outer periphery on the movable element. When fire occurs in the vicinity of the valve, heat is conducted to the fusible element which softens or melts and is shorn away under the weight or combined weight and spring pressure on the movable member and moves to closed position. An important feature of my invention is the provision of guide means for the movable element whereby it is moved into accurate seating position to shut off the valve.

For a further exposition of my invention reference may be had to the annexed drawings and specification at the end whereof my invention will be specifically pointed out and claimed.

In the drawings,

35 Figure 1 is a vertical cross section of one modification of my device.

Figure 2 is a vertical cross section of another modification.

Figure 3 is a vertical cross section of a third modification.

Figure 4 is a side elevation showing my valve as applied to a meter.

Figure 5 is a side elevation with parts in cross-section of another modification.

45 Figure 6 is a vertical cross section showing yet another modification, and

Figure 7 is a side view with parts broken away of still another modification.

In the embodiment of my invention chosen 50 for illustration in the drawings, my device is shown as used in conjunction with a standard gas meter 10 which forms no portion of my invention and which is simply illustrated to show the location in which my novel valve is used.

55 Gas meter 10 is supplied with gas through an

inlet pipe 11. My novel valve, generally indicated at 12, is located between the inlet pipe 11 and the meter 10. The meter is also provided with gas outlet pipe 13.

Referring now to Figure 1 for the specific details of my novel valve consists generally of a valve casing 15 having an inlet port 16 and an outlet port 17 therein, the outlet port 17 having a valve seat 18 adjacent its upper end. Located in valve casing 15 there is provided a movable valve element 19 having a tapered face 20 adapted to cooperate with seat 18 to close the valve outlet 17 and to thereby shut off the gas supply to meter 10. Movable element 19 is carried in casing 15 by a guide element 21 which embraces the upper part of the movable element 19. Guide member 21 also carries stationary member 22 which carries at its lower end fusible element 23 which is shown as consisting of a centrally perforated disk but which may conveniently take any other form suitable for supporting the movable element. Fusible element 23 is attached to stationary element 22 by means of a nut 24 engaging the rim of the disk surrounding its central perforation, or in any other convenient manner. Movable element 19 is supported on fusible element 23 by means of bushing 25 which has contact on its lower face with the outer portion or rim of the fusible element 23 and which has screw thread or other connection with movable element 19. It is to be noted that the internal diameter of bushing 25 is slightly greater than the external diameter of stationary member 22 so that movable element 19 falls freely when fusible element 23 shears or melts due to heat being conducted to it.

In Figure 2 there is illustrated a modified form of my device having all the elements of Figure 1 which perform equivalent functions and having in addition a spring 26 interposed between guide member 21 and bushing 25 so that movable member 19 is stressed to valve closed position by gravity and by the initial pressure of spring 26. It will, therefore, be seen that when fusible member 23 softens or melts due to the heat applied thereto the combined forces of the weight of movable element 19 and the pressure of spring 26 tend to shear fusible element 23 and to permit movable element 19 to close outlet 17 by seating at 18.

In Figure 3 there is disclosed a slightly different modification of my valve in which casing 15 is a plug cock of angular type or it can be a three-way plug cock. Casing 15 is provided at inlet 16 with a seat 118. Casing 15 carries at its upper end an additional stationary member 122 which supports member 22 in it. Stationary

110

member 22 carries at its lower end an internal guide member 121 which passes through an orifice in the movable member 19. Movable element 19 is supported on the fusible element 23 by means of bushing 25. Movable element 19 has beneath the fusible element 23 a cavity 119 which may receive the molten metal in case the fusible element 23 melts. Guide 121 serves to locate movable element 19 when it falls so that the movable element closes orifice 118 and thereby shuts off the valve. This is a very important feature as it prevents the plug 19 from injuring the surfaces of the inside of the plug cock while it is dropping into place.

15 The construction shown in Fig. 3 is a conventional plug cock which closes off port 118 or, in the case of a three-way cock, it would close both ports, viz 118 and a similar port opposite to 118. The angle cock shown in Figure 3 will be closed off when port 118 only is closed.

20 In Figure 5 there is disclosed a modified form of my novel valve similar to that disclosed in Figure 2 except that the casing 115 has a bar 30 made integral therewith. The bar 30 corresponds 25 to the detachable bar shown between the inlet pipe 11 and the outlet pipe 13 in Figure 4 and serves to connect my novel shut-off valve with the union 31 to which the gas offtake pipe 13 from the meter 10 is attached. Valve casing 115 has 30 its outlet 17 connected to a goose neck pipe 32 which is connected by a union 33 with the inlet pipe 34 of meter 10. The outlet pipe 37 of meter 10 is connected by union 36 with a goose neck pipe 35 which in turn connects with offtake pipe 13 35 through union 31. Casing 115 may also have, if desired, either integral therewith or attached thereto a cock casing 126 which has mounted therein a movable cock element 127, said movable element having at one end a washer 128 which 40 secures it in position in the casing 126 so that it is free to rotate. By means of this cock the passage of gas to the heat responsive valve in casing 115 may be cut off.

45 Figure 6 shows a modified form of valve similar to that disclosed in Figure 3 and has a seat 125 opposite to seat 118 and serving to admit fluid to outlet 117.

50 In Figure 7 there is shown yet another modified form of valve in which the casing 15 has a stud 99 as a part thereof. Stud 99 carries on its outer surface screw threads or other detaching means 98 which serve to support the valve in place. In practice this modification is used by exposing the stud 99 to the heat of a boiler, water heater or 55 other device in accordance with whose temperature it is desired to operate the valve. It will thus be seen that when stud 99 is exposed to a predetermined temperature heat is conducted to the

fusible member 23 within the valve which melts or is shorn and permits the movable element to close the valve.

I do not intend to be limited in the practice of my invention save as the scope of the prior art 80 and of the attached claims may require.

I claim:

1. A gas meter fire valve including in combination a valve casing having a valve seat therein, a movable element normally suspended above said valve seat, a guide member within said casing and passing through said movable element, and a fusible element supporting said movable element, and adapted upon being heated to cause said movable element to close against said valve 90 seat.

85 2. A heat responsive shut-off valve including in combination a valve casing having ports therein, a movable element cooperating with one of said ports to open and close it, a fusible element retaining said movable element in valve open position, means on said movable element for holding a portion of said fusible element on at least two faces, and means carried by said casing 95 for holding another portion of said fusible element on at least two faces.

100 3. A heat responsive shut-off valve comprising a casing having a fluid way therein, a movable element tending to close said fluid way, a perforated element adapted to soften under the influence of heat and interposed between a fixed portion carried by the casing and the movable element, means for clamping one rim of said perforated element at both faces of the element in respect to said casing, and means for clamping 105 the other rim of the element at both faces of the element in respect to the movable element.

110 4. A heat responsive shut-off valve including in combination a casing having an opening for the passage of gas therein, a movable element for closing said opening, a fusible element supporting said movable element, means on said casing for clamping a portion of said fusible element on at least two faces of said portion, and means on 115 said movable element for clamping another portion of said fusible element on at least two faces of said portion.

120 5. A heat responsive shut off valve device for gas meters comprising in combination a valve casing having a stoppered opening and having an inlet gas way for the meter, a slideable valve body, a guide for the valve body, a fusible element supporting said valve and insertable and removable through the stoppered opening, and said 125 valve provided with a recess into which the fused element runs.
